UNITED STATES PATENT OFFICE.

JOHN B. YARNELL, OF JOHNSTOWN, PENNSYLVANIA, ASSIGNOR OF ONE-HALF TO
F. B. COOK, OF JOHNSTOWN, PENNSYLVANIA.

RAILROAD TRACK AND TIE.

1,356,584.

Specification of Letters Patent. Patented Oct. 26, 1920.

Application filed May 26, 1920. Serial No. 384,372.

To all whom it may concern:

Be it known that I, JOHN B. YARNELL, a citizen of the United States, residing at Johnstown, in the county of Cambria and State of Pennsylvania, have invented certain new and useful Improvements in Railroad Tracks and Ties, of which the following is a specification.

This invention relates to certain new and useful improvements in railways and more particularly to the tracks, having special relation to what I term mine trackage, having for its objects among others to provide a simple yet efficient and durable and reliable form of rail and tie, when a tie is employed, although in some instances I provide what may be termed a tieless rail, designed more especially for mines where it is desirable to change the track at intervals and to keep the height of the track down as low as possible. The invention is applicable also to turn-out switches and frogs, as will hereinafter appear.

The invention has for a further object to provide a rail that can be put down and taken up in a short time and without the necessity of skilled labor. In one form of the invention the employment of spikes or bolts is dispensed with, as the steel tread rail cannot lift out from the ties. I may employ either a steel or a wooden tie. The joints between the abutting ends of two rails are formed in a simple and cheap yet efficient manner, and by using channel steel I provide a strong rail which is capable of manufacture at comparatively small cost.

Other objects and advantages of the invention will hereinafter appear and the novel features thereof will be specifically defined by the appended claims.

The invention, in its preferred forms is clearly illustrated in the accompanying drawings, which, with the numerals of reference marked thereon, form a part of this specification, and in which—

Figure 1 is a plan view of a switch and turn-out showing the application of my invention.

Fig. 2 is an enlarged section on the line 2—2 of Fig. 1.

Fig. 3 is an enlarged section on the line 3—3 of Fig. 1.

Fig. 4 is a vertical cross section through a track with the wheels of a car broken away

and shown in elevation, other parts being in elevation.

Fig. 5 is a plan with parts in section showing the rails and the tie in accordance with my invention.

Fig. 6 is a perspective view of two sections of my tieless mine track with the sections united.

Fig. 7 is a similar view showing the rail sections before they are joined together.

Like numerals of reference indicate like parts throughout the several views.

Referring to the drawings—

1 designates a steel tie which is formed near each end with the channel portion 2 which is designed to be received and fit snugly within the channel 3 of the steel rail 4. This rail has the lateral flanges 5 at each edge as seen in Fig. 4 to rest upon the tie, and when suitable bolts 6 are passed horizontally through the interengaged channel portions of the tie and rail and the nuts 7 applied, a very efficient trackage is provided possessing maximum strength and durability.

In lieu of the steel tie I may employ a wooden tie as seen in Fig. 5 at 8, the said tie having rigid therewith near each end the block or member 9 at right angles to the length of the tie as shown clearly in Fig. 5, which blocks fit into the channels of the rail 10 at each end of the tie and the rail sections and blocks secured firmly together by means of the bolts 11 passed through opposite sides of the channel portions of the rails and the said blocks and receiving nuts 12 as shown in said Fig. 5.

In Fig. 1 I have shown how channeled rails such as above described may be employed for frogs and switches or turn-outs. In this view the adjacent ends of two rail sections are secured together by means of blocks 13 with the ends of each block entering the channel of the two rails and secured by bolts or the like 14, as seen in Figs. 2 and 3, the blocks 13 being secured to the tie by means of vertical spikes or the like 14, as shown in Fig. 2.

In all instances the rails are channeled and the coöperating parts are received in the channels of the rails. This applies, whether the rails be used for the track, the frog or switch, as will be readily understood by reference to Fig. 1.

In building a frog blocks of steel should be employed, riveted to the steel plate 15, see Fig. 1, and the tread section should be welded or riveted to such blocks in a well known way.

Fig. 1 clearly indicates how the track continues from the turn-out by using the channeled rail and the steel or wooden tie, with its blocks, in the manner above described 10 in connection with Figs. 4 and 5.

In Figs. 6 and 7 I have shown a tieless mine trackage. In this form the track is of double channel form, the channel upon one side being reverse of that upon the opposite 15 side. In this form the adjacent ends of two rails are secured together by means of the member 16 having one end secured in the one channel 17 of the one rail 18 by means of the bolts 19, or the like, the other end of the 20 member 16 projecting beyond the end of the rail 18 and adapted to enter the channel 17 of the adjoining rail 20 and to be secured therein by means of the bolts or other means 21, as seen in Fig. 6.

25 This tieless mine rail takes care of the car by the construction of the rail, that is, the flanges of the car wheels always remain in the grooves or channels 22 of the rails,

and these rails, resting on the rock bottoms, have no chance to bed themselves. Therefore, the car will either draw the rails together or push them apart and thus automatically provide the proper gage.

Modifications in detail may be resorted to without departing from the spirit of the 35 invention or sacrificing any of its advantages.

What is claimed as new is:—

1. A railroad rail of double channel form and a tie having interlocking connection 40 with said rail.

2. A railroad rail of channel form, and a tie having a transverse member fitted in the channel of the rail.

3. A railroad rail of channel form, combined with a steel tie having a channel portion near each end to fit within the channels 45 of the rails of a track.

4. A railroad rail of channel form, combined with a tie having a transverse member 50 fitted within the channel of the rail, and means passed through the walls of the channel of the rail and through said member.

In testimony whereof I affix my signature.

JOHN B. YARNELL.
